UNITED STATES PATENT OFFICE.

LEWIS HALLOCK NASH, OF BROOKLYN, ASSIGNOR TO THE NATIONAL METER COMPANY, OF NEW YORK, N. Y.

CASE FOR ROTARY WATER-METERS.

SPECIFICATION forming part of Letters Patent No. 408,507, dated August 6, 1889.

Application filed January 13, 1886. Serial No. 188,462. (No model.)

To all whom it may concern:

Be it known that I, LEWIS HALLOCK NASH, a citizen of the United States, residing at Brooklyn, in the county of Kings and State of New York, have invented new and useful Improvements in Water-Meters, of which the following is a specification.

My present invention consists of improvements in water-meters, and is illustrated in the drawings forming part of this specification as applied to a meter now well known in the trade as the "Crown," which is fully described in patents granted to me January 21 and 28, 1879, Nos. 211,582 and 211,769, and July 17, 1883, No. 281,390. Said patent granted January 21, 1879, was reissued February 8, 1887, No. 10,806 of reissues. My present invention is, however, obviously applicable to other forms of meters than those described in said patents.

My improvement is directed to the construction of the chamber-wall of a water-meter, whereby it is rendered more durable and easily repaired when such wall or case becomes worn from the friction of the piston. For this purpose I apply to the bearing-surface of the case, or to some portions of it, a facing of hard metal of the desired form, and a backing, preferably of soft metal, introduced as a filling to lock the hard-metal facings to the wall, whereby the smooth hard surface of the metal of the piston (made preferably of hard rubber) permits an easy movement to the piston. This construction gives the advantage of making it possible to remove and replace the worn metal facings by new ones, and in this particular the meter can be repaired so as to make it as good as new.

In my patent aforesaid of July 17, 1883, the joint-forming bearings of the case-wall are provided with a soft-metal facing cast directly upon the wall projections, so as to be locked therewith, whereas in my present improvement, as embodied in the form illustrated in the drawings, I use a soft-metal filling or backing of cementing substance as the means of securing a hard-metal facing for the case projections, and find the meter to be thereby made more durable at the points subject to wear.

In the accompanying drawings I have shown

so much of the crown water-meter as illustrates the joint-forming construction of the case-wall projections, in which Figure 1 shows the interior of the meter-case in top view, 55 and Fig. 2 a horizontal section of the same, with the piston in the relation it occupies in dividing the chamber into receiving and discharging measuring-spaces; and Fig. 3 shows an enlarged horizontal sectional detail of a 60 portion of the case and one of its wall-bearing projections provided with my improvement. Fig. 4 is a vertical sectional view of the meter, taken through line xx of Fig. 1. Fig. 5 shows the inner side of the hard-metal 65 facing of the projection; Fig. 6, its top edge, and Fig. 7 its bottom edge.

Referring to Figs. 2, 3, and 4, it will be seen that the case-wall is formed with projections f , which are at equal distances apart around the 70 chamber, and are of such form, dovetail or otherwise, as to make a lock for a soft-metal filling or cement backing e , which in turn forms a lock for a hard-metal facing formed to suit the form of the piston projections and 75 recesses, as shown. I prefer to use a soft-metal filling, because when applied in a molten condition it hardens with perfect adhesion to the walls of the case and of the facing.

The hard-metal facings shown are of a hollow form with a convex part a , which terminates in side wings a' a' , having faces curved parallel with the circle of the inner wall of the case-chamber, so as to suit the movement of the piston, while the inner hollow side of the facing is of such shape as to form locks b at two or more points with the soft-metal backing. This soft-metal backing not only forms a filling for the hollow convex part a of the facing, but forms a seat for the 80 wings of the facing, so that the locking-points b a^2 of the facing stand inward at the opposite sides of the dovetail case projections, while the ends of the latter stand into the hollows of the hard-metal facings, and thereby form 85 a very effective securement for the latter. While the soft-metal filling is locked to the chamber-wall projections, as stated, they are also fastened thereto by being lapped over and under the ends of said projections, as 90 shown in Fig. 4.

The hard-metal facings may be applied and

secured in any suitable manner. They may, for instance, be set and held within the case-chamber in position to be permanently fixed thereto by means of a suitable core centered 5 in said chamber, there being a space between each facing and the projection to receive the soft-metal filling, which is poured into said spaces in a molten condition; but as such apparatus and method of manufacture are made 10 to the subject of a separate application by me, filed of even date herewith under Serial No. 188,463, a more particular description thereof is deemed unnecessary here.

I prefer to cast the chamber-forming case 15 integral with the interior wall projections, as shown, and subsequently complete the joint-forming bearings, as stated; but they may be cast separately, if desired.

I claim—

- 20 1. A water-meter case formed of a series of alternate projections and recesses having the bearing-surfaces of its chamber-wall formed of hard metal, and a backing of cementing metal or material, substantially as described.
- 25 2. A water-meter case formed of a series of alternate projections and recesses, having the bearing-surfaces of its chamber-walls formed of hard-metal facing, a backing of cementing metal or material, and wall-locks, substantially as described.
- 30 3. In a water-meter, the combination of an inclosing-case, separated and isolated bearing-surfaces formed of hard metal, and a

cementing metal or material uniting said hard-metal bearing-surfaces and case, substantially 35 as described.

4. In a water-meter, the combination of an inclosing-case, separate and isolated bearing-surfaces formed of hard metal, and a cementing metal or material uniting and locking to 40 said metal bearing-surfaces and case, substantially as described.

5. The water-meter case formed with inner wall dovetail projections, in combination with a bearing-surface of hard metal, and a cementing material cast over the wall projections and locked with said hard-metal facings, substantially as described.

6. The combination, with the chamber-forming body cast in one piece, of interior chamber-wall projections formed of hard-metal facings, and a backing of cementing substance, substantially as described.

7. In a water-meter, the combination of the piston having circumferential projections, 55 with a chamber-forming case having wall projections of soft metal, and a facing of hard metal permanently fastened thereto, substantially as described.

In testimony whereof I have hereunto set my 60 hand in the presence of two subscribing witnesses.

LEWIS HALLOCK NASH.
